UNITED STATES PATENT OFFICE.

FRANK J. REICHMANN AND JOHN PRESS, OF CHICAGO, ILLINOIS; SAID PRESS
ASSIGNOR TO SAID REICHMANN.

TELEPHONE INSTRUMENT.

1,347,175.

Specification of Letters Patent. Patented July 20, 1920.

Application filed June 21, 1918. Serial No. 241,135.

To all whom it may concern:

Be it known that we, FRANK J. REICHMANN and JOHN PRESS, citizens of the United States, residing at Chicago, in the 5 county of Cook and State of Illinois, have invented a new and useful Telephone Instrument, of which the following is a specification.

Our present invention relates to improvements in telephone instruments and more especially to a novel form of carbon receptacle particularly suited for use on an amplifier in loud-speaking telephone circuits. The invention will be fully understood from 15 the following specification, taken in connection with the accompanying drawings, in which—

Figure 1 is a sectional view through the operating mechanism of the carbon button; 20 Fig. 2 is a section on the line 2 of Fig. 1; Fig. 3 is an enlarged section through a modified form of the button; Fig. 4 is an enlarged face view of the spring-spider employed in our improved button; and Fig. 5 25 is a side elevation of a different construction of the button.

The construction illustrated by Figs. 1 and 2 is substantially the same as that described and claimed in our co-pending application, Serial No. 241,134, filed June 21, 1918, and will therefore be described only 30 briefly in the present specification. As here shown, it comprises a head 10, of generally disk-like form and having secured to its back a modified horseshoe magnet 11, made up of two laminations. A stud pole-piece 12 secured to both laminations at one end of the magnet has a spool-winding 13 thereon. The other pole of the magnet is formed 35 by bending upwardly or outwardly the extremity of the upper lamination to bring it substantially into the plane of the face of the stud 12. This bent extremity has a knife-edge pivot 15 formed thereon, which 40 serves to balance an armature 16, the outer end of which extends over the stud pole 12, clearing the latter by a few thousandths of an inch, while the inner end extends to the approximate center of the head and there 45 has secured in an aperture a link 17, which forms a connection to the carbon button. The armature 16 is held in place on the knife-edge pivot by a pin-and-socket bearing formed by an overhanging flexible arm 18. The upturned extremity of the magnet 50

is adjusted toward and away from the plane of the magnet by a wedge-screw 19, which flexes this upturned extremity to increase or decrease the clearance between the armature and the stud-pole-piece. 60

The carbon button, to the construction of which our present invention particularly relates is housed within a cup-shaped metal casing 20, the flanged open end of which is secured directly to the outer face of the 65 head 10.

In Fig. 3 there is shown a modified form of cup-casing, designated 20 and having an integral neck 20_a, which is fastened by a set-screw in the boss of a bridge-piece 20_b, this 70 arrangement being useful in connection with an ordinary type of telephone transmitter. In Fig. 5 the cup-casing designated 20_c is formed integrally with a transmitter diaphragm 20_d. The internal construction of 75 the button, as fitted within these different forms of casings, is as follows.

In the base of the cup there is mounted a carbon disk 21, upon which there bears an insulating annulus formed, for example, of 80 asbestos and of considerable thickness, as shown at 22. A disk of asbestos paper 23 rests upon the opposite face of the annulus 22, this disk being secured by a shouldered annulus 24. Within the space formed by 85 the inner shoulder of the annulus 24 there is secured a spring-spider 25 and a second asbestos paper disk 26. Spacing washers 27 interposed between the center of the paper disks 23, 26 and the spider 25, hold 90 the latter in the dished shape illustrated. The link 17 extends through central apertures in the asbestos paper sheets 23, 26 and the spider 25, and by means of nuts serves to secure against the faces of the sheets 23 and 26 carbon-disk electrodes 28, 29, of approximately the shape and size shown. Within the space formed by the outer shoulder of the annulus 24 there is secured a thin carbon disk 30, which is backed or reinforced by a brass annulus 31, which likewise 95 serves as one of the electrode terminals of the button. The brass disk 31 is insulated from the cup 20 by a mica annulus 32, of the full diameter of the interior of the cup. An outer metallic washer or annulus 33 holds 100 all of the parts in their assembled positions and is itself secured, as for example, by nicking the metal of the cup, as shown at 34, to force the margin thereof inwardly at 105 110

a plurality of points around the periphery or, optionally, continuously around the periphery. An insulating and packing gland for the metallic link 17, where the latter passes through the carbon disk 30, is formed by a wad of fluffy asbestos, designated 35. The separate interior chambers within the button are each filled with granular carbon, designated 37.

10 Although we have shown and described in considerable detail a preferred embodiment of our invention as used in connection with some particular forms of vibration producing or reproducing means, it will be understood that this is illustrative only and for the purpose of making the invention more clear and that the invention is not limited to the details of construction mentioned nor to the use of the instrument described, except in so far as such limitations are included within the terms of the accom-

panying claims, in which it is our intention to claim all novelty inherent in our invention as broadly as is permissible in view of the prior art.

25

What we regard as new and desire to secure by Letters Patent is:

1. In a carbon button for telephony, a compound diaphragm dividing the mass of granular carbon into separate portions and comprising a dished, flexible disk-like member secured between resilient sheets.

2. In a carbon button for telephony, a compound diaphragm dividing the mass of granular carbon into separate portions and comprising a central flexible metallic member having insulating sheets on both faces and spaced away from the metallic member at the center and in contact therewith at the periphery.

FRANK J. REICHMANN.
JOHN PRESS.
